[57] **CLAIM**

The ornamental design for an element for an athletic shoe upper, as shown and described.

DESCRIPTION

FIG. 1 is a right side elevational view of the element for an athletic shoe upper showing my new design;

FIG. 2 is a left side elevational view of the athletic shoe shown in FIG. 1;

FIG. 3 is a top plan view of the athletic shoe shown in FIGS. 1 and 2; and,

FIG. 4 is a front elevational view of the athletic shoe shown in FIGS. 1-3.

The broken line showings of an athletic shoe are for illustrative purposes only and form no part of the claimed design.
